UNITED STATES PATENT OFFICE.

GUSTAVUS MILLIISER, OF RICHMOND, VIRGINIA, ASSIGNOR TO THE
MILLIISER MANUFACTURING COMPANY, OF SAME PLACE.

DESIGN FOR A TOBACCO-PACKAGE.

SPECIFICATION forming part of Design No: 29,851, dated December 20, 1898.

Application filed November 26, 1898. Serial No. 697,562. Term of patent 14 years.

To all whom it may concern:

Be it known that I, GUSTAVUS MILLIISER, a citizen of the United States, residing at Richmond, in the county of Henrico and State of Virginia, have invented and produced a certain new and useful Design for Tobacco-Packages, of which the following is a specification, in which—

Figure 1 is a plan view, and Fig. 2 a side elevation, of the package.

My design consists of a cloth or textile package having an oval substantially flat base *a* and an oval substantially flat top *b*, the edge *c* of the package being continuous and standing at right angles to the upper and lower faces. On the upper face is formed a series of radiat-

ing plaits or folds *d*, which extend from a central opening *e* to the edge in the manner of a rosette. Over the opening is a bow-knot of cord or twine *f*.

The package is the same vertical thickness throughout, the upper and lower faces being substantially parallel.

I claim—

The design for a tobacco-package substantially as herein shown and described.

In testimony whereof I affix my signature in presence of two witnesses.

GUSTAVUS MILLIISER.

Witnesses:
